CLAIM

The ornamental design for a pair of table legs, as shown and described.

DESCRIPTION

FIG. 1 is a front elevation view of a pair of table legs showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a perspective view thereof, shown within an environment of use.

In FIG. 7, the broken lines depict environmental subject matter that forms no part of the claimed design.
